(57) CLAIM

I claim the ornamental design for a "rake stand set," as shown.

DESCRIPTION

FIG. 1 is a perspective view of the rake stand set;
FIG. 2 is a top plan view of the head stand;
FIG. 3 is a right side elevational view thereof;
FIG. 4 is a bottom plan view thereof;
FIG. 5 is a front side view thereof, the opposite side view is a
mirror image;
FIG. 6 is a top plan view of the pole stand;
FIG. 7 is a right side elevational view thereof;
FIG. 8 is a bottom plan view thereof; and,
mirror image.

The elements of the claimed design are shown separate for ease and clarity of illustration.

The broken lines showing a rake are for the purposes of illustrating environment and forms no part of the claimed design.
